US0D1078927S

(12) **United States Design Patent** (10) **Patent No.:** **US D1,078,927 S**
(45) **Date of Patent:** **** Jun. 10, 2025**

(54) **BACK-MOUNTED SPRAY APPARATUS**

(71) Applicant: **Invatech Power Equipment Inc.**,
Vancouver (CA)

(72) Inventor: **Rick Juric**, Vancouver (CA)

(73) Assignee: **Invatech Power Equipment Inc.**,
Vancouver (CA)

(**) Term: **15 Years**

(21) Appl. No.: **29/807,403**

(22) Filed: **Sep. 10, 2021**

(51) **LOC (15) Cl.** **23-01**

(52) **U.S. Cl.** **D23/223**
USPC **D23/223**

(57) **CLAIM**

The ornamental design for a back-mounted spray apparatus, as shown and described.

DESCRIPTION

FIG. 1 is a front, right side, top perspective view of the back-mounted spray apparatus;

FIG. 2 is a front elevation view thereof;

FIG. 3 is a rear elevation view thereof;

FIG. 4 is a sectional view thereof shown in fragment and taken along lines 4-4;

FIG. 5 is a right side elevation view thereof;

FIG. 6 is a left side elevation view thereof;

FIG. 7 is a top plan view thereof; and,

FIG. 8 is a bottom plan view thereof.

The dashed broken lines depict portions of the back-mounted spray apparatus that form no part of the claim.

1 Claim, 8 Drawing Sheets
